UNITED STATES PATENT OFFICE.

EDMUND C. MORGAN, OF MORGAN PARK, ILLINOIS.

MINING MACHINE.

1,424,114.

Specification of Letters Patent. Patented July 25, 1922.

Application filed June 27, 1910, Serial No. 569,168. Renewed January 7, 1918. Serial No. 210,796.

To all whom it may concern:

Be it known that I, EDMUND C. MORGAN, a citizen of the United States, residing at Morgan Park, in the county of Cook and 5 State of Illinois, have invented certain new and useful Improvements in Mining Machines, of which the following is a specification.

This invention relates more especially to 10 that type of mining machines which are drawn along the wall of a drift or tunnel while they are being continuously operated.

The main general object of this invention is to provide an improved construction, 15 combination and arrangement of parts according to which a machine of this character can be simply and durably constructed and made rapid and efficient in action.

The primary object is to provide an im- 20 proved cooperating arrangement between the cutting, breaking down and removing mechanisms.

Another object is to provide improved 25 automatic means for breaking down the coal during the progress of the cutting operation.

More particularly it is the object of the 30 present invention to provide mechanism for cutting a plurality of spaced-apart horizontal kerfs and a vertical kerf spaced back from the face of the mine wall to effect the cutting of columns or cores of coal in position to be 35 acted upon by a plurality of superposed pick machines to break down the coal into the range of operation of the conveyer which is provided with a scooping receiving end adapted to travel in the plane of the lowermost horizontal kerf.

Other and further objects will appear in 40 the specification and be specifically pointed out in the appended claims, reference being had to the accompanying drawings exemplifying the invention, and in which-

Figure 1 is a general plan view of a mining machine constructed in accordance with 45 the principles of this invention.

Figure 2 is a side elevation of the same.

Figure 3 is a plan view of a conveyor for loading the coal on to the cars.

Figure 4 is a side elevation of the same.

50 Figure 5 is a plan view of an attachment for the machine whereby the coal as it is broken down may be ejected into the path of the endless chain conveyer.

Figure 6 is a side elevation of the same.

Figure 7 is a top plan view of a modified 55 construction of the ejector attachment.

Figure 8 is a side elevation of the same.

Figure 9 is a plan view showing diagrammatically the operation of the ejector co-operatively arranged with an ejector plate. 60

Figure 10 is a diagrammatic elevation of the same.

Figure 11 is a detail section on the line XI—XI, Fig. 1.

Fig. 12 is a detail plan view of the rear 65 portion of the machine, partly in cross section;

Fig. 13 is an end view in cross section on the line 13—13 of Fig. 12.

Referring more especially to the embodiment shown in the drawings, the mining machine is provided with a base member 1 which is adapted to slide along the floor of a drift or gallery, travel being imparted to said base member by means of a drum 2 70 keyed to a shaft 3 to which motion may be imparted from a worm wheel 4 through the agency of a clutch 5 provided with a shifting lever 6, which is operated in a well known manner. A cable 7 wound upon the drum 2 75 and secured by a hook 8 to a strut 9, serves to draw the machine along the wall of coal or other material 10. A motor 11 of any suitable construction is provided with a drive shaft 12, to which is keyed at the forward end thereof a driving worm 13 meshing with the worm wheel 4. Immediately to the rear of the motor 11 is mounted a side frame comprising uprights 14, 15 and cross bar 16. Rotatably mounted in the base member 1 and an overhanging bracket arm 17 of said side frame is a cutter shaft 18 on which are 80 keyed a plurality of cutter heads 19 for making horizontal kerfs within the side wall 10, and also an under cutting cutter head 20. 85 Also keyed to the cutter shaft 18 is a spiral gear 21, by means of which the cutter shaft 18 is rotated from a spiral worm 22 keyed to the drive shaft 12. Journalized within a projecting portion 23 of the upright 15, and a bracket 24 mounted on the base member 1, is a second cutter shaft 25, upon one end of which is keyed a large side cutter 26. For 90 driving this cutter for making a vertical slot in the wall 10, said cutter bar 25 is provided with a spiral gear 27 keyed thereto, with

90

85

95

100

105

which meshes a spiral worm 28 rigidly secured to the drive shaft 12 in any suitable manner. The cutters thus far described are adapted to cut the vertical slot 29 (see Fig. 1) and the horizontal slots 30, 31, 32 and 33, shown in Fig. 4 and Fig. 10.

In order to provide efficient means for breaking down the coal between the several slots, a plurality of picking devices are mounted on the frame and provided with means for automatically projecting them into the wall 10. These picking devices, which are preferably three in number, to correspond with the three ridges of coal, will now be described.

An upper picking device comprises a reciprocable rod 34 slidably mounted in a boss 35 on the cross bar 16, and also supported by a pedestal 36. Projecting laterally from the reciprocable bar 34, is a cam arm 37, between which and the boss 35 is disposed a resilient member, preferably a spring 38, which spring, when the bar 34 is forced rearwardly, tends to return the bar 25 to its normal position, shown in Fig. 1. A washer or flanged projection 39 is preferably employed for an abutment for one end of the spring 38. In order to provide means for holding the pick bar 34 temporarily, after the spring 38 has been compressed, the latch or lever 40 pivoted at 41 upon a lug rigid with the boss 35 is provided. This lever 40 is maintained in the path of the washer 39 by a compression spring 42, so that whenever said bar 34 is forced rearwardly, a detent 43 on the end of the lever 40 slips over and engages said washer 39. A vertical shaft 44, which is rotatably mounted in the base member 1, and a bracket 40 arm 45 overhanging from the upright 15, serve to mount a cam plate 46 for each picking device, said cam plate being adapted to force the arm 37 with the bar 34 rearwardly until the washer 39 is engaged by the detent 43. Said shaft 44 has mounted thereon a worm gear 47 which meshes with a spiral worm 48 keyed to drive shaft 12. Exactly similar picking devices are reciprocably mounted upon the bars 49 and 50 mounted in a similar manner below the bar 34. Each of said reciprocating picks will therefore be moved into retracted position once each time the shaft 44 is completely rotated. Detent lever 40 is adapted to be oscillated to release any one of said picks by means of a handle 51, which may be grasped by the hand of the operator, or, if it be desired to make the action continuously automatic, a protuberance 52 may be provided on the handle end of the lever 40 in suitable position to be engaged by a roller on the end of a crank arm 53 rigidly secured to an upright shaft 54, which is rotatably mounted in a boss 55 on the base member 1, and a bracket arm 56 projecting

from the upright 14. A spiral gear 57, which is also keyed to the shaft 54, meshes with a spiral worm 58 on the drive shaft 12.

Referring now to Figs. 1, 2, 3 and 4, suitable means for conveying the cut coal rearwardly from the machine for loading into suitable cars is provided by means of an endless chain conveyer 59 provided with laterally projecting arms 60, which move about the chain sprockets 61 and 62 shown 75 diagrammatically on the drawings. The lower chain sprocket 62 is keyed to the upright shaft 44 and derives its movement therefrom. A chute 63 provided with a side rail 64 serves to support and guide the 80 material as it is delivered to the car 65, as shown in Fig. 4. As shown in Figs. 1 and 4 the receiving end of the conveyer comprises a plate at the lower end of the chute 63 and in the plane of the lowermost horizontal kerf.

In order to provide means for holding the machine against the side wall 10 during its operation, a plurality of struts or posts 66 are employed, which press directly against the outside edge of the base member 1. As the cutting operation proceeds, it becomes necessary to remove the struts 66 out of the path of the upper end of the conveyer chute 63. For this purpose, a hammer 67 is 95 mounted on an oscillable shaft 68 which shaft is provided with a projection 69 disposed to be engaged by one end 70 of a bent lever pivoted intermediately of its ends upon a pin 71 rigidly mounted in the base 100 frame 1. A second lever 72 provided with a detent arm 73 is adapted to engage a projection 74 on said shaft 68. Said lever 72 is provided with an outwardly curved portion 75, which is adapted to be drawn 105 against a post 66 for setting the hammer 67, said hammer being held by the lever 70 engaging the projection 69. An outwardly projecting arm 76, which, as the machine is drawn forward, is engaged by 110 the post 66, serves to force the detent 70 out of engagement with the projection 69, thus allowing the hammer 67 to deliver a blow on the post 66 under the action of a spring 77, which blow knocks the post 66 115 down, after which it may be set up in another position in the rear of the machine, as shown at 66' in Fig. 1.

Referring now to Figs. 5 and 6, means are shown for ejecting the coal which has been 120 broken down by the picking device 34, into the path of movement of the conveyer. This ejector is provided in the form of an attachment comprising an ejector bar or lever 78, pivotally supported from the base member 1, by means of a pin 79 which passes through the base member 1, and is provided below with an apertured portion 80 within which the bar 78 slides. The outer end of the ejector bar 78 is hollowed to provide a plate 130

portion 81 and a vertically projecting back or web 82. Means for oscillating the ejector bar is provided by a gear 83 mounted on a shaft 84 extending through the base member 1, and having a crank arm 85 keyed thereto on the other side of the base member 1, there being a crank pin 86 rigidly mounted on the arm 85 and pivotally engaging the ejector bar 78. Motion may be imparted to the gear 83 by a driving pinion 87 connected with the driving shaft 12.

Referring now to Figs. 7 and 8 which show a modification of the ejector device, the ejector bar 78' is pivotally connected with the base member 1 at 80', the outer end of the bar being similarly formed to that in the other embodiment. In the modification, however, said ejector bar is adapted to be oscillated by means of an eccentric 88, which 20 is keyed to a short vertical shaft 89 rotatably mounted in the base member 1 and provided with a gear 83' driven by a pinion 87'.

A device for further assisting the ejection of the coal into the path of the conveyer is shown in Figs. 9 and 10, and consists of a substantially wedge-shaped block or chute 90 which is adapted to be introduced into the under cut 33 formed by the lowermost cutter of the machine. Said block 90 is 30 formed with a cavity in its upper inclined face and tapers away from the column of coal which is being broken down. When a lump of coal 91 drops upon the wedge-shaped block 90, it assumes the position 35 shown in Fig. 10, and has imparted to it a tendency to slide forwardly so that when the end 81 of the ejector bar engages it behind, it becomes easily dislodged, and is thrown on to the lower end of the chute 63 40 in the path of the conveyer.

In order to provide means for minimizing the quantity of loose particles and dust suspended in the air about the mining machine and which is produced during the cutting and breaking down operations, an air-displacing device is made use of which in the present embodiment comprises a rotary fan 93 rigidly mounted on a vertical shaft 94. The fan 93 is preferably disposed immediately under the motor 11, the upper end of the shaft 94 having a flanged pulley 95 keyed thereto and driven by an endless belt 96, said belt being adapted to transmit power from a flanged pulley 97 on the motor shaft 12, by means of guide pulleys 98. An intake trough 99 is connected by means of a channel or passageway 100 with an axial opening into the fan housing. Said intake trough is elongated as shown in Figure 2 to extend approximately the full height of the gallery or drift within which the machine is at work so that the fan exhausts the dust laden air from all stratas. As shown in Figure 1, the intake opening of the trough 65 99 is made to conform to the path of the

horizontal grooving cutters. A discharge outlet or pipe 101 projects tangentially from the fan housing which may be connected up in any suitable manner with any receptacle or chamber (not shown on the drawings) in 70 which it may be desired to collect the dust and dirt.

In my copending application Serial No. 98,438, filed June 27, 1910, I have broadly claimed some of the subject-matter in common with the disclosure herein, and in my divisional application Serial No. 76,910, filed Feb. 8, 1916, I have described and claimed the loading apparatus and the combination of the loading apparatus with the pick machine both disclosed in the present application Serial No. 210,796.

What I claim is:

1. In a machine of the character described, the combination with means for making two horizontal kerfs in the material to be mined, of means for making a vertical kerf intersecting said horizontal kerfs to form a column, and picking means disposed between the horizontal kerf-making means and operating from the machine directly against the exposed surface of the mine wall for breaking down sections from said column.

2. In a machine of the character described, the combination with means for making a plurality of horizontal kerfs in the material to be mined, of means for making a vertical kerf intersecting said horizontal kerfs to form a plurality of columns, and picking means disposed between each pair of the horizontal kerf-making means and transverse to the vertical kerf-making means for breaking down the material by action directly against the exposed mine wall surface of said columns.

3. In a mining machine, the combination with a base member movable along a wall of the material to be mined, of a plurality of rotating cutters arranged to cut parallel horizontal grooves, a vertically disposed rotary cutter arranged to cut a groove intersecting said horizontal grooves, a picking device arranged between each pair of adjacent horizontal cutters, and a motor operably connected to each of said cutters and picking devices.

4. In a mining machine, the combination with a base member movable along a wall of the material to be mined, of a plurality of rotating cutters arranged to cut parallel horizontal grooves in said wall, a vertically disposed rotary cutter arranged to cut a groove intercepting the bottoms of said horizontal grooves, a reciprocating pick mounted between each pair of horizontal cutters, and means mounted on said base for reciprocating said picks and rotating said cutters simultaneously.

5. A mining machine embodying a horizontal grooving tool, a vertical grooving

tool, and picking means between said tools and operating from the machine for breaking down the material to be mined.

6. In a mining machine, a base member movable along a wall of material, a horizontal cutter mounted on said base member to project beyond the side thereof, a vertical cutter mounted on said member to overhang on the same side as said horizontal cutter, and a picking device mounted on said base member at an angle between the mounting of said cutters.

7. In a coal mining machine, the combination with a base member movable along a coal wall, of a vertical rotary shaft, a plurality of horizontal cutters keyed to said shaft and adapted to cut parallel horizontal kerfs in said wall, a horizontal rotary shaft extending transversely of the base member, a vertical cutter keyed thereto and adapted to cut a slot intercepting said horizontal kerfs, and means mounted on said base member between said shafts for breaking down the coal after the action of said cutters.

8. In a coal mining machine, the combination with a base member movable along a coal wall, of a vertical rotary shaft, a plurality of horizontal cutters keyed to said shaft and adapted to cut parallel horizontal kerfs in said wall, a horizontal rotary shaft extending transversely of the base member, a vertical cutter keyed thereto and adapted to cut a slot intercepting said horizontal kerfs, means mounted on said base member between said shafts and operable from the machine for breaking down the coal after the action of said cutters, and a conveyer having one portion disposed beneath said breaking down means.

9. In a coal mining machine, the combination with a base member movable along the coal wall, of a vertical rotary shaft, a plurality of horizontal cutters keyed to said shaft and adapted to cut parallel horizontal kerfs in said wall, a horizontal rotary shaft extending transversely of the base member, a vertical cutter keyed thereon and adapted to cut a slot intersecting said horizontal kerfs, and means mounted on said base member between said shafts and operating from the machine for breaking down the coal after the action of said cutters.

10. In a coal mining machine, the combination with a base member movable along the coal wall, of a vertical rotary shaft, a plurality of horizontal cutters keyed to said shaft and adapted to cut parallel horizontal kerfs in said wall, a horizontal rotary shaft extending transversely of the base member, a vertical cutter keyed thereto and adapted to cut a slot intersecting said horizontal kerfs, and means mounted on said base member between said shafts and operating independently of the movement of the ma-

chine for breaking down the coal after the action of said cutters.

11. In a mining machine, the combination with a plurality of kerf cutters rotating in approximately horizontal planes spaced apart, of an additional kerf cutter operating in a vertical plane at right angles to the horizontal kerfs and at the bases thereof, a plurality of automatically-operated picking devices for dislodging from the mine wall in lumps the material cut out by said horizontal and vertical kerf cutters, and means for conveying away from the mine wall the dislodged material.

12. The combination with a plurality of kerf cutters, pick mechanism for dislodging material cut by said kerf cutters, means for conveying away from the mine wall the material dislodged by said pick mechanism, means for operating said kerf cutters, pick mechanism and conveying means, a frame for carrying the aforesaid parts, posts for guiding said frame and holding it near the mine wall to permit said kerf cutters and pick mechanism to act thereon, means for slowly feeding the machine forward during operation, and mechanism for automatically loosening the guide posts when the conveying means approach said posts.

13. In a mining machine, the combination with a plurality of rotary cutters for producing kerfs in a mine wall in horizontal planes spaced apart, an additional kerf cutter operating in a vertical plane at right angles to the horizontal kerfs and at the bases thereof, pick mechanism for dislodging the material cut out by said kerf cutters, conveying apparatus for removing from the mine wall the material dislodged by said pick mechanism, pneumatic apparatus for removing dust and fine particles of material produced by said kerf cutters, feeding mechanism for slowly moving the machine along the mine wall during the operation of said kerf cutters and said pick mechanism, a frame for carrying the aforesaid parts, vertical posts for guiding said frame and holding the same near the mine wall as it is moved forward, and automatic mechanism for loosening the posts one after another as each is approached by said conveying apparatus.

14. A mining and loading machine comprising a supporting frame, mechanism mounted on said frame for cutting a column by cutting on both sides of a body of material in a mine wall and at the back thereof, so as to cut all around the same, and power mechanism mounted on said frame adjacent said column-cutting mechanism for effecting mechanically the transfer of the cut material from its cut position in the mine wall toward loading position independently of the operation of said column cutting mechanism.

15. A mining and loading machine com-

- prising a supporting frame, means for cutting a rectilinear core of material in its native bed in a mine by cutting on both sides of the core and at the back thereof, conveyor mechanism connected to said frame and movable therewith to be continuously in position for loading the material, and intermediate mechanism mounted on said frame ahead of the receiving portion of said conveyor mechanism and adjacent thereto for effecting mechanically the transfer of the cut material directly from the mine wall to said conveyor mechanism.
16. A mining and loading machine comprising a supporting frame, mechanism mounted on said frame for cutting in a mine wall a rectilinear section of material, and means mounted on said frame in position for automatically taking the dislodged material from the mine wall where cut and effecting the transfer thereof toward loading position.
17. A mining and loading machine comprising a supporting frame, core-cutting mechanism mounted on said frame and extending therefrom, means for operating said core-cutting mechanism to cut on both sides and at the back of the core in a mine wall to produce a rectilinear core, a conveyor mounted on said frame in position for receiving dislodged material, and mechanism mounted on said frame for movement relatively thereto and in position to act on the material substantially in the space originally occupied thereby in its native bed to transfer substantially all of such material onto said conveyor.
18. A mining and loading machine comprising a supporting frame, mechanism mounted on said frame for cutting a core of material in a mine wall, means for operating said core-cutting mechanism including rectilinear feeding of said supporting frame along the mine wall, means in position on said frame for transferring dislodged material from the mine wall toward loading position, and mechanism on said frame extending therefrom to a position ahead of the receiving means for moving the dislodged material over the mine floor onto said receiving means.
19. A mining and loading machine having supporting frame-work in common, core-cutting mechanism mounted on said frame-work in position for cutting rectilinear cores in a mine wall adjacent said frame-work, and loading apparatus mounted on said frame-work in fixed relation thereto for taking the material directly from its originally occupied position in the mine wall and moving it toward loading position.
20. A mining and loading machine comprising a supporting frame, means comprising a plurality of spaced-apart kerf-cutters mounted on said frame for dislodging ma-
- terial from the mine wall in the form of rectilinear columns, a conveyor connected to said frame and movable bodily therewith, and means for acting on the material in the position which it assumes after being dislodged to slide such material onto said conveyor.
21. A mining and loading machine comprising a supporting frame, kerf-cutting mechanism mounted thereon, means for operating said kerf-cutting mechanism including the feed thereof to cut a rectilinear core of material in a mine wall, conveying mechanism mounted on said frame in fixed relation thereto, and means mounted on said frame and movable relatively thereto to act on the material at the mine wall to transfer the same onto said conveyor.
22. A mining and loading machine comprising a supporting frame, a plurality of separate kerf-cutters mounted thereon, means for operating said kerf-cutting mechanism including rectilinear feed thereof to effect the cutting of a kerf above a rectilinear core of material, at the back thereof spaced from the face of the mine wall and below the core, a conveyor mounted on said frame in fixed relation thereto, and power mechanism mounted on said frame for delivering the material of said core to said conveyor.
23. A mining and loading machine comprising a supporting frame, means comprising a plurality of plane kerf-cutters mounted on said frame for dislodging material from a mine wall in the form of rectilinear cores, a loading conveyor mounted on said frame in fixed relation thereto, and apparatus comprising a vertical device mounted on said frame for moving the dislodged material onto said conveyor.
24. A mining and loading machine comprising a supporting frame, mechanism mounted thereon for cutting a solid rectilinear core of material along a mine wall, means mounted on said frame for dislodging the cut material, and mechanism in position on said frame for taking the dislodged material from its native position and moving it toward loading position at the rear of said frame.
25. A mining and loading machine comprising a supporting frame, means mounted on said frame for cutting a single rectilinear core of material in its native bed in a mine, means mounted on said frame in position for breaking the core into large blocks independently of movement of said frame, and means mounted on said frame for moving the dislodged blocks of material from the mine wall relatively to said frame and toward loading position independently of the movement of said frame.
26. A mining and loading machine comprising a frame, means mounted thereon for cutting a rectilinear core of material in its

- native bed adjacent said frame, mechanism mounted on said frame in position to act directly on the core while still in its native position for breaking sections from such 5 core during the operation of said core-cutting means, and mechanism mounted on said frame in position for taking dislodged material immediately after being dislodged and moving the same toward loading position 10 while said core-cutting means continues in operation.
27. A mining and loading machine comprising means for cutting spaced-apart kerfs at the sides of a rectilinear column of 15 material in its native bed and also a communicating kerf at the back of such column, a supporting frame for such cutting means, conveyer mechanism mounted on said frame and extending from a position near the cutting 20 mechanism rearwardly toward loading position, and means mounted on said frame for effecting the transfer of the cut material directly from the mine wall onto said conveying mechanism.
- 25 28. A mining and loading machine comprising a supporting frame, mechanism mounted thereon, and extending therefrom to cut a core of material along a mine wall, means mounted on said frame and extending 30 therefrom on the side from which said cutting mechanism extends for dislodging the cut material, and conveyer mechanism connected to said frame and movable bodily therewith in position for taking the 35 dislodged material and moving it diagonally across the rear end of the machine.
29. A mining and loading machine comprising a supporting frame, means mounted thereon and extending therefrom to cut a 40 rectilinear core of material in a mine wall adjacent said frame, endless conveyer mechanism mounted on said frame in predetermined relation thereto and for movement bodily therewith, and intermediate mechanism on said frame and extending from a 45 position at the same side of the frame from which said core-cutting mechanism extends for effecting the transfer of dislodged material from the mine wall onto said conveyer 50 mechanism.
30. In a mining and loading machine, the combination with mechanism for cutting a core in a mine wall in one operation, of mechanism connected to the machine for 55 acting on the core to dislodge the same during the operation of said cutting mechanism, apparatus for operating said dislodging mechanism at intervals, and means for receiving the dislodged material and moving 60 it toward loading position.
31. In a mining and loading machine, the combination with a portable frame, of means comprising separate spaced-apart kerf-cutters mounted thereon for dislodging 65 material from a mine wall onto the floor adjacent said frame, loading apparatus connected to said frame to move bodily therewith, and means mounted on said frame intermediate the dislodging means and said loading apparatus for pushing the material 70 off the mine floor into position to be operated upon by said loading apparatus.
32. A mining and loading machine comprising a supporting frame, a pick mounted thereon and extending therefrom toward a mine wall adjacent said frame, means for automatically holding said pick in retracted position at spaced-apart intervals, automatic mechanism for repeatedly releasing said holding means to cause said pick to strike 80 intermittent blows against the mine wall to dislodge material therefrom, a conveyer mounted on said frame and extending to a predetermined receiving position in fixed relation to said frame, an ejector mounted 85 on said frame in position for operating on the material where dislodged by said pick, and means for operating said ejector to move the material dislodged by said pick to the receiving end of said conveyer. 90
33. A mining and loading machine comprising a supporting frame, means mounted thereon for cutting upper and lower spaced-apart kerfs in a mine wall and an additional kerf spaced back from the face of the mine 95 wall in an upright plane transverse to the plane of said spaced-apart kerfs, mechanism mounted on said frame for movement relatively thereto and relatively to said cutting means for dislodging the cut material, 100 and loading apparatus mounted on said frame to move bodily therewith and extending to a receiving position adjacent the range of operation of said dislodging mechanism.
34. A mining and loading machine comprising a longitudinal frame, mechanism mounted on said frame for cutting a core of material along a mine wall at one side of said frame, means on said frame extending transversely thereof and laterally therefrom 110 to act transversely on said core to dislodge material therefrom, and conveyer mechanism mounted on said frame to move bodily therewith and extending to a receiving position for taking the dislodged material from the 115 longitudinal side of the machine adjacent the mine wall and moving such dislodged material diagonally across the path of the machine toward loading position.
35. A mining and loading machine comprising means for cutting a rectilinear core of material from its native bed by cutting spaced-apart kerfs and a back kerf leaving the core bounded by such kerfs and the face of the mine wall and leaving the core 120 integral at one end with the material in its native bed, a frame for supporting said cutting means, means on said frame and movable relatively thereto adjacent said cutting means for breaking the core into large blocks, 125 130

and means on said frame adjacent said breaking means and movable bodily with said frame for automatically moving the dislodged blocks of material from the mine wall 5 toward loading position.

36. A mining and loading machine comprising means for cutting a core of material from its native bed by cutting kerfs all around the core except at the face of the mine wall and except its integral connection at one end with the unmined mass, a pick machine acting directly on the core in its original position at the mine wall for breaking said core after being cut, a frame for 10 supporting said cutting means and said pick machine adjacent to each other and adjacent to the mine wall, and mechanism mounted on said frame for automatically taking the dislodged material from its position at the mine wall immediately after being broken 15 down and moving the same toward loading position.

37. A mining and loading machine comprising a supporting frame, means mounted 20 on said frame for cutting spaced-apart kerfs and a rear upright plane intersecting kerf to effect the cutting of a core of material in a mine wall bounded by the face of the mine wall, upper and lower flat surfaces and 25 the rear flat surface, conveyer mechanism mounted on said frame in spaced relation with said core-cutting means and movable bodily with said frame, and mechanism on 30 said frame intermediate said core-cutting means and said conveyer mechanism for operating movement relative to said frame for transferring the dislodged material onto 35 said conveyer mechanism.

38. A mining and loading machine comprising a supporting frame, an upright kerf cutter for cutting a kerf in an upright plane spaced back from the face of the mine wall and intersecting a plurality of previously 40 cut transverse kerfs, a shaft mounted on said 45 frame and extending therefrom to said kerf cutter, means for operating said kerf cutter including the feed thereof transversely of 50 said shaft, means for dislodging the cut material in advance of said shaft, and loading 55 apparatus mounted on said frame for receiving the dislodged material and conveying it toward loading position.

39. A mining and loading machine comprising a frame, kerf-cutting mechanism 60 mounted on said frame, means for moving said frame and said cutting mechanism bodily to effect feeding of said cutting mechanism, means for actuating said cutting mechanism during the forward feed of said frame, breaking mechanism connected to 65 said frame and movable bodily therewith during the forward feed thereof to act on the material extending back of said cutting mechanism, mechanism for effecting inter-

nism automatically during the forward feed of said cutting mechanism, and conveyer mechanism connected to said frame and movable bodily therewith and extending to a position to receive the dislodged material 70 and convey it toward loading position.

40. A mining and loading machine comprising a longitudinal frame, a plurality of horizontal spaced-apart kerf cutters projecting from one side of said frame, an upright 75 kerf cutter spaced back from the mine wall, supporting mechanism extending from said frame to said upright kerf cutter to hold the same spaced back from the mine wall behind said first-named kerf cutters and in position 80 to cooperate with said first-named kerf cutters to cut a body of material parallel to the path of said frame and adjacent thereto, loading apparatus connected to said frame and comprising a traveling conveyer extending to a receiving position on that side 85 of the frame from which the said kerf cutters extend and which move along the mine wall adjacent thereto, and means for operating said kerf cutters and said loading apparatus including the bodily forward feed of the entire machine to mine and load a body 90 of material from one side of the path of the machine and parallel to such path to the other side of said machine and parallel to 95 such path.

41. A mining and loading machine comprising a longitudinal frame, means mounted on said frame adapted to effect feeding movement thereof in its longitudinal direction, a plurality of kerf cutters extending laterally from said frame, an upright kerf cutter spaced back from the face of the mine wall, a horizontal shaft for said upright kerf cutter and mounted on said frame back of 100 said spaced-apart kerf cutters, a plurality of picks mounted on said frame ahead of said horizontal shaft and extending laterally from said frame to act on the cores produced by said kerf cutters, mechanism for automatically operating said picks to dislodge 105 material from said cores, an endless conveyer at the rear end of said frame and extending from a receiving position at one side of said frame adjacent said upright kerf cutter, a 110 driving shaft extending longitudinally of said frame, power transmission gearing between such driving shaft and said kerf cutters, between such driving shaft and such conveyer and between such driving shaft 115 and the automatic mechanism for operating said picks, ejector mechanism also connected for operation to said driving shaft and extending laterally from said frame beneath the picks and ahead of the receiving end of 120 said conveyer, and a motor mounted on said frame and connected to said driving shaft and also to the said means for moving said frame in its longitudinal direction.

42. A mining machine comprising a sup- 125

- porting frame, of a horizontal grooving tool extending from one side thereof, a vertical grooving tool mounted on said frame and located at that side thereof on which said horizontal grooving tool is mounted, and picking means mounted on said frame between said tools in position to operate laterally from said frame for breaking down material cut by said grooving tools.
43. A mining and loading machine comprising a supporting frame, a plurality of spaced-apart kerf-cutters including an under-cutting tool extending outwardly from said frame to operate adjacent the floor of a mine, a second cutter mounted on said frame and spaced therefrom to operate transversely of the first-named cutters to loosen material from its native bed in a mine, means for driving said cutters, a conveyor mounted on said frame, and means for moving dislodged material into the range of operation of said conveyor.
44. In a mining machine, the combination with kerf-cutting mechanism, of a pick machine, a conveyor, an ejector for removing the material dislodged by said pick machine and kerf-cutting mechanism into the path of said conveyor, and mechanism for operating said ejector and said pick machine in synchronism to cause said ejector to act automatically immediately after the operation of said pick machine.
45. In a mining machine, the combination with kerf-cutting mechanism, of a pick, automatic mechanism for reciprocating said pick to cause the same to strike hammer blows against the mine wall to dislodge the material therefrom adjacent the kerfs produced by said kerf-cutting mechanism, a conveyor, an ejector, and means for operating said ejector in automatic synchronism with said pick-operating means to cause said ejector to push said ejector into position for moving said dislodged material immediately after the pick is pushed into the mine wall.
46. A mining and loading machine comprising a supporting frame, means mounted thereon for cutting upper and lower spaced-apart kerfs in a mine wall and an additional kerf spaced back from the face of the mine wall in an upright plane transverse to the planes of said spaced-apart kerfs, mechanism mounted on said frame for movement relatively thereto and relatively to said cutting means for dislodging the cut material, and loading apparatus extending to a receiving position adjacent the range of operation of said dislodging mechanism.
47. A long wall mining machine comprising a plurality of spaced-apart parallel kerf-cutters, a vertical kerf-cutter following said parallel kerf-cutters and spaced from the mine wall to effect the cutting of a core of material in the mine wall leaving the forward end integral therewith, and mechanism intermediate the parallel kerf-cutters and said vertical kerf-cutter to break said core of material.
48. In a mining machine, the combination with a plurality of kerf-cutters spaced-apart, of means for operating said kerf-cutters to produce parallel spaced-apart kerfs along the mine wall, a vertical kerf-cutter spaced back from the face of the mine wall and having a shaft perpendicular to the mine wall, and means for breaking down the cut material ahead of said shaft.
49. In a mining machine, the combination with a plurality of kerf-cutters, an additional kerf-cutter operating in a plane at right angles to the planes of said first-named kerf-cutters, and means located between the first-named kerf-cutters and said second-named kerf-cutter for dislodging from the mine wall a core of material cut out by all of said kerf-cutters.
50. In a mining machine, the combination with a frame, of means for feeding said frame along a mine wall, a plurality of kerf-cutters spaced-apart mounted on said frame, means for operating said kerf-cutters to produce a plurality of horizontal spaced-apart parallel kerfs in the mine wall, a vertical kerf-cutter spaced back from the mine wall, and pick mechanism back of said horizontal kerf-cutters and ahead of the shaft of said vertical kerf-cutter for dislodging from the core material severed by said kerf-cutter.
51. A long wall mining machine comprising a supporting frame, a plurality of spaced-apart kerf-cutters mounted on said frame for producing parallel kerfs in substantially horizontal planes, a vertical kerf-cutter spaced from the face of the mine wall to co-operate with said horizontal kerf-cutters to cut a core of material in a mine wall and extending back along the same, said vertical kerf-cutter having a shaft extending from said frame, pick mechanism operating behind the horizontal kerf-cutters and head of the shaft of the vertical kerf-cutter for dislodging the core, and conveyor mechanism mounted on said frame for taking the dislodged material and moving it toward loading position.
52. A mining machine comprising two spaced-apart kerf-cutters for producing substantially horizontal parallel kerfs in a mine wall, a vertical kerf-cutter spaced from the face of the mine wall and cooperating with said horizontal cutters to cut a core of material in the mine wall, and means acting on the core to dislodge the material therefrom before the central portion of said vertical kerf-cutter approaches said core.
53. A mining machine for dislodging parallelepipeds from a mine wall comprising a plurality of kerf-cutters operating in substantially horizontal planes to produce par-

- allel spaced-apart kerfs in a mine wall, a vertical kerf-cutter spaced back from the face of the mine wall, a shaft for said vertical kerf-cutter substantially perpendicular to the mine wall, means for operating the horizontal kerf-cutters and said vertical kerf-cutter, and pick mechanism for acting on the cut material before approach by said shaft for dislodging such material substantially in the shape of parallelepipeds.
54. A mining machine comprising a supporting frame, a plurality of kerf-cutters mounted on said frame for producing substantially horizontal kerfs in a mine wall spaced-apart and substantially parallel with each other, a vertical kerf-cutter spaced back from the mine wall, a horizontal shaft for said vertical kerf-cutter located on said frame substantially perpendicular to said mine wall, means for operating said horizontal kerf-cutters and said vertical kerf-cutter, pick mechanism mounted on said frame to be automatically operated for intermediately dislodging the backward projecting core of material cut by said kerf-cutters, and conveyer mechanism mounted on said frame for taking the dislodged material and moving it toward loading position.
55. In a mining and loading machine, the combination with core-cutting mechanism, of means for operating the same including continuously acting feeding mechanism, intermittently operated pick mechanism for dislodging the core of material, and loading apparatus comprising conveyer mechanism in position to receive the dislodged material and carry it toward loading position.
56. The combination with a main frame movable laterally along a coal face, of a horizontally projecting cutter to undercut the coal, a plate arranged to move in the plane of the kerf cut by said undercutter, a conveyer extending in operation from points outside the coal face to points innermost the line of the kerf and arranged to follow the lines of travel of a cutter and to have said plate deliver coal thereto, motor and power mechanism on the main frame in front of the conveyer, and means for breaking the coal down adapted to attack the coal above the under-kerf at an angle to the front face of the coal.
57. In a mining and loading machine, the combination with a supporting frame, of cutting mechanism mounted thereon and comprising an undercutting kerf-cutter, loading apparatus comprising a traveling conveyer and a chute mounted in fixed relation to said supporting frame and having a receiving scooping end in the plane of the under kerf and extending to points near the innermost line of the under kerf in position to scoop up dislodged coal as the machine is advanced along the coal face, and means for operating said cutting mechanism including feed thereof by movement of said frame while said conveyer and chute are carried bodily therewith.
58. In a mining and loading machine, the combination with a supporting frame movably laterally along the coal face, of a horizontally projecting cutter to undercut the coal, means mounted on said frame to dislodge the coal above the under kerf and form a continuously advancing face substantially at right angles to the normal coal face, loading apparatus comprising a traveling conveyer and a chute mounted on said frame and having a receiving plate arranged to move in the plane of the under kerf back of said advancing coal face in position to scoop up the dislodged coal, means for driving said undercutter, and means for moving said frame along the coal face to effect feeding movement of said undercutter and scooping operation of said plate.
59. In a mining machine, the combination with a portable supporting frame, of core-cutting mechanism having an unobstructed opening therethrough for the passage of the core extending parallel to the path of travel of said portable frame, means comprising an electric motor for driving said core-cutting mechanism, rope-winding mechanism mounted on said frame and comprising a rope with its free end adapted to be anchored in a mine chamber, transmission gearing between said motor and said rope-winding mechanism, and a clutch for controlling the connection of said transmission gearing to said rope-winding mechanism to effect the operation of the latter and the feeding of said core-cutting mechanism independently of the driving of said core-cutting mechanism.
- In testimony whereof I have signed my name to this specification, in the presence of two subscribing witnesses, on this 21st day of June, A. D., 1910.
- EDMUND C. MORGAN.
